Dec. 878

A. S. Vedder, of Troy, N.Y.
Assignee
John S. & Merritt Peckham, of Utica, N.Y.
Letters Patent No. 878. Dated Mar. 24. 1857.

The Schedule referred to in these Letters Patent and making part of the same.

To all whom it may concern:

Be it known that A. S. Vedder, of the City of Troy, in the County of Rensselaer, and State of New

Dec. 878

York, have invented or produced a new and original design for a Cooking Stove called the Artizan and I do hereby declare that the following is a full and exact description of the same, reference being had to the accompanying drawings, and to the letters of reference marked thereon.

Figure 1, is a perspective view of the stove. Letter A, the front plate; letters B.B, the front doors; letter C, the side plate; letters D.D, the side doors, letters E.E, the feet.

What I claim as my invention or production, and desire to secure by letters patent, is.

The general design and configuration of said stove.
